UNITED STATES PATENT OFFICE.

FERDINAND THIELKE, OF BROOKLYN, NEW YORK.

DESIGN FOR A HANDLE FOR BUTTON-HOOKS.

SPECIFICATION forming part of Design No. 28,390, dated March 22, 1898.

Application filed December 29, 1897. Serial No. 664,477. Term of patent 3½ years.

all whom it may concern:

Be it known that I, FERDINAND THIELKE, a citizen of the United States, residing at Brooklyn, in the county of Kings and State of New York, have invented and produced a new and original Design for Handles for Button-hooks and Like Articles, of which the following is a specification, reference being had to the accompanying drawing, which shows a perspective view of my newly-designed handle applied to a button-hook.

The leading feature of my design consists in the outline, as shown, consisting of compound curves, the outer end of the handle having a plain central portion and terminating in a leaf-like scroll, and the lower end of the handle separated from the outer end by leaf-like ornamentation having raised lines terminating in a leaf-like scroll at the extreme outer end of the handle.

A represents the handle, having the outline of contour as shown, the outer end of the handle terminating in the leaf-like scroll B, and having a plain central shield C, bordered by raised lines D. The lower end of the handle 25 has raised lines or ribs E, terminating in the ornamentation F, the lower portion of said handle being separated from the outer end of the handle by the leaf-like scroll or ornamentation G.

30

What I claim is—

The design for a handle for button-hooks, and similar articles, substantially as herein shown and described.

FERDINAND THIELKE.
